UNITED STATES PATENT OFFICE

2,456,089

WIDE BAND FREQUENCY MODULATOR

Eugene R. Shenk, Brooklyn, and Anthony Liguori,
New York, N. Y., assignors to Radio Corpora-
tion of America, a corporation of Delaware

Application June 26, 1946, Serial No. 679,339

9 Claims. (Cl. 179—171.5)

1

This application concerns a new and improved frequency modulator, particularly adapted for use at low frequencies such as, for example, audio frequencies.

In some systems known in the art frequency modulation in the audio range has been achieved with the use of two oscillators in the low radio frequency range beating against each other. For example, in Fig. 2 of Whitaker U. S. Patent 2,289,157 a pair of oscillators o and o' operating at frequencies separated by a small frequency band are used as described above for production of frequency modulated currents of low frequency. In this patented arrangement the oscillators o and o' operate at slightly different radio frequencies. One of the oscillators o' is modulated in frequency by currents or potentials derived by scanning and by other potentials. The oscillatory energy generated in the two oscillators are applied to separate grids in the converter tube 76 and the difference frequency is taken from the output of the converter. The difference beat note derived from the two oscillators is also modulated in frequency and is selected for signaling purposes. Other systems of this type and systems which are more complicated are known in the prior art.

As will be seen by consideration of the system described above an oscillator and a mixer stage, in addition to the modulated oscillator, are used in this type system. Moreover, in the two oscillator systems as described above a small percentage frequency drift in either of the oscillators results in a large percentage frequency drift in the audio frequency output.

An object of my invention is provision of a wave length modulator adapted for timing modulation of carrier currents in the relatively low frequency or audio range in which system very little frequency drift in the audio frequency output can take place.

Another object of my invention is provision of a relatively inexpensive timing modulator supplying a relatively low frequency output with little or no frequency drift. In using the term "frequency modulation" applicant does not exclude modified frequency modulation or phase modulation or modulation having the characteristics of either frequency or phase modulation. Moreover although I have described the carrier as being of low or audio frequency obviously it may be of high or low frequency.

These main objects are accomplished in accordance with my invention by use of the current from a pentode tube integrated in a capacitor con-

nected in a trigger or locking circuit having one condition of stability to which it tends to return. The arrangement is such that when the voltage across the capacitor reaches a critical magnitude the trigger circuit trips from its stable condition and discharges the capacitor in a very short time. Then the circuit returns to its stable condition and the capacitor is allowed to recharge. Modulating current or voltage is applied to the pentode grid to control the magnitude of the current through the pentode and thereby produce frequency modulation of the trigger circuit by controlling the rate at which the capacitor is charged and discharged and as a consequence the repetition rate at which the trigger circuit is fired to discharge the capacitor.

In one application of my invention the output is taken from the trigger circuit described briefly above. In another application the modulated trigger circuit controls a multivibrator which divides by two. Both system require only one oscillator operating at an audio frequency rate.

In pentodes tubes the current is constant for any one value of grid voltage irrespective of changes in the anode potential so that a linear increase or decrease in signal voltage results in a linear increase or decrease in output frequency over very wide limits, for example, in an embodiment of my invention a 20 volt change in signal voltage results in a frequency shift from 2,000 cycles per second to 12,000 cycles per second.

Although it is believed that applicant's invention as described hereinabove will be fully understood by those skilled in the art details of the same and the manner in which it is applied will now be described. In this description reference will be made to the attached drawings wherein Figs. 1 and 2 each illustrate a different embodiment of my capacitor controlled trigger circuit with the means for controlling the charge of the capacitor in accordance with signals. In the embodiment of Fig. 2 a multivibrator circuit is connected to the modulated trigger circuit and the multivibrator is assumed to have a factor of division of two.

Fig. 3 illustrates by voltage waveforms the manner in which the modulators of Figs. 1 and 2 operate.

In Fig. 1 of the drawing, VI may be designated the modulator tube. Its grid 4 is connected to the high potential side of a modulating signal input circuit the low potential side of which is grounded. The grid 4 is connected to the negative terminal of a biasing source C by resistor 6. The cathode 55 is also connected to this source by a fixed resistor

8 and variable resistor 10. The screen grid is connected to a point between resistors 12 of a potential divider circuit one end of which is grounded as is the positive terminal of the source C. The tubes V2 and V3 are connected in a trigger circuit of the general type shown in Finch U. S. Patent 1,844,960. The anode of the tube V1 is connected to one side of a capacitor C1 the other side of which is connected to ground. The anode of tube V1 is also connected to the cathode of tube V2 and to the anode of a diode tube V4 the cathode of which is grounded putting the tube V4 in shunt to capacitor C1. The anode of tube V2 is connected to a direct current source by resistor 16 and to the control grid of tube V3 by capacitor C2. The anode of V3 is connected by resistor 22 to the grid of tube V2 and to ground so that the anode is supplied with a direct current potential which is positive relative to its cathode because the cathode is connected to the negative terminal of the said source. The grid circuit of tube V2 includes a resistor 20 while the grid circuit of tube V3 includes a resistor R1. The resistor 22 is shunted by a capacitor 26. Resistors 20 and 22 are proportioned to provide suitable direct current biasing voltage for the grid of V2. Capacitor 26 constitutes a short circuit across 26 for alternating currents.

In the embodiment illustrated the tube V2 is normally non-conductive since its grid is held negative with respect to ground by the potential drop produced in resistor 22 due to current flow in the tube V3 which is normally conductive. If the point P is grounded tubes V2 and V3 are in a triggering circuit operating as described above. V3 is normally conductive because its cathode and grid are held at essentially the same potential by the resistor R1. The arrangement is such that when current flows in tube V3, which takes place when the grid and cathode are of about the same potential, the potential drop in resistor 22 is applied to the grid at tube V2 to cut this tube off. Application of a less negative potential to the control grid of V2 will cause current to flow in tube V2 to cut off current flow in the tube V3. This permits the charge on the condenser C2, built while tube V2 was non-conductive, to decrease. While this charge in the condenser C2 is decreasing the discharge current flowing through resistor R1 develops a negative potential on the control grid of tube V3 to reduce current in this tube. When the current is reduced in tube V3 the potential drop in resistor 22 decreases to make the control grid in tube V2 relatively more positive. The action is accumulative and current is switched through tube V2 and cut off in tube V3. This condition remains until the grid of tube V2 is again caused to or permitted to become sufficiently negative, in which case the locking or triggering circuit returns to its original condition of stability at which current flows in tube V3 is cut off in tube V2.

In operation modulation on the control grid 4 of tube V1 varies the intensity of the current through tube V1. Current flows from the plate 7 of tube V1 to condenser C1 thereby charging this condenser negative at its anode end and positive at its ground thereby driving the cathode of tube V2 negative with respect to ground. The grid of tube V2 is normally held negative with respect to ground as described hereinbefore. As soon as the cathode of tube V2 becomes negative enough, that is, takes on a potential about like the grid potential, tube V2 starts conducting, thereby discharging condenser C1 through tube

V2. By the tripping action described above V3 is cut-off. Tube V2 on being tripped to the conductive state conducts for a time at least as long as the time required to discharge condenser C1. The time constant C2R1 of the triggering circuit which determines the active time of the trigger circuit is slightly greater than the time required to discharge condenser C1, but the diode V4 supplies a path for the additional current to keep tube V2 conducting after capacitor C1 is fully discharged.

The current flow from the tube V1 to condenser C1 is constant for any one value of grid signal voltage on tube V1 despite the variations in plate voltage on the plate 7 of tube V1. Tube V1, therefore, supplies a constant current to C1 in the presence of constant modulation potential irrespective of variations in the potential at the point P. Any linear increase or decrease in signal voltage results in a linear increase or decrease in current flow to capacitor C1. Since capacitor C1 charges to the same voltage value each time before discharging the frequency produced by the triggering circuit including tubes V2 and V3 is a function 25 of the magnitude of the current flow through tube V1 which in turn follows the signal potentials.

Where pulse type output is desired the embodiment of Fig. 1 is used. Where sine wave output 30 operation is required a multivibrator is connected to the plate of tube V2. The arrangement then is as illustrated in Fig. 2 wherein the tubes V5 and V6 are in the multivibrator circuit. The operation of the multivibrators are so well known 35 in the art that a detailed description thereof is thought unnecessary here. The repetition rate of the multivibrators depends, as is well known, on the capacitors and resistors in the cross-coupled circuits. The anodes of the multivibrator tubes V5 and V6 are supplied by potentials from the same source used to supply the triggering circuit 40 through resistor 16. To do this the anodes of tubes V5 and V6 are connected by resistors 30 and 32 to the anode of tube V2. Now as the anode potential of tube V2 rises and falls in accordance 45 with the signal modulations corresponding potential variations are applied to the anodes of tubes V5 and V6 in the multivibrator circuit to modulate its frequency in accordance with the signals. 50 In this operation then the multivibrator is synchronized by the pulses appearing at the anode of tube V2 and at half the modulator frequency. A low pass filter is connected to the multivibrator and this filter passes the fundamental frequency 55 plus the modulation side bands. The filter output is sinusoidal in form.

Figure 3 shows the voltage wave forms as they appear in different parts of the circuit. Line A shows the voltage across condenser C1, a linear 60 charge and a short time discharge. The discharge pulses as they appear on the plate of V2 are shown in line B. The pulses synchronize the multivibrator at one-half the modulator frequency and result in the square waves as shown in line C. These 65 appear at the input to the low pass filter. The output of the low pass filter is a sinusoidal wave as shown in line D.

What is claimed is:

1. A timing modulation system including in combination, a trigger circuit including two electrode structures with their electrodes cross-coupled by resistors and capacitors in such a manner that current normally flows in one electrode structure and is cut off in the other electrode structure, a capacitor connected to an electrode

of one electrode structure to include the same in a path for said capacitor wherein current or potential is developed to control the charge in said capacitor to thereby control the potential on said electrode, a modulator tube having output electrodes in a second charge controlling circuit for said capacitor, and means for controlling the current through said modulator tube in accordance with signals.

2. A timing modulation system as recited in claim 1 wherein said modulator tube is of the type wherein anode current depends primarily on grid potential rather than anode potential.

3. A timing modulation system including in combination, a trigger circuit including two tube structures with their electrodes cross-coupled by resistors and capacitors in such a manner that current normally flows in one structure and is cut off in the other structure, a capacitor connected to an electrode of said other structure to include the same in a discharge path for said capacitor and to control the potential on said electrode, a modulator tube having output electrodes in a charging circuit for said capacitor, and means for controlling the current through said modulator tube in accordance with signals.

4. A timing modulation system as recited in claim 3 wherein said modulator tube is of the type wherein anode current depends on grid potential rather than anode potential.

5. A timing modulation system including in combination, a trigger circuit including two tubes with their electrodes cross-coupled by resistors and capacitors in such a manner that current normally flows in one tube and is cut off in the other tube, a capacitor connected to an electrode of one tube to include the same in a path for said capacitor wherein current or potential is developed to control the charge in said capacitor to thereby control the potential on said electrode, a modulator tube having output electrodes in a second charge controlling circuit for said capacitor, a multivibrator coupled to an electrode in one of said first named tubes, and means for controlling the current through said modulator tube in accordance with signals.

6. A timing modulation system as recited in claim 5 wherein said modulator tube is of the type wherein anode current depends primarily on grid potential rather than anode potential.

7. A timing modulation system including in combination a trigger circuit including two tubes with their electrodes cross-coupled by resistors

and capacitors in such a manner that current normally flows in one tube and is cut off in the other tube, a capacitor connected with one tube electrode to control the potential thereon, a modulator tube having input electrodes excited by signals and having output electrodes and a coupling between the output electrodes of said modulator tube and said capacitor.

8. A timing modulation system including in combination, a trigger circuit including two tubes with their electrodes cross-coupled by resistors and capacitors in such a manner that current normally flows in one tube and is cut off in the other tube, a capacitor connected with an electrode of said other tube to control the potential thereon and thereby control its state of conduction, and a modulator tube excited by signals and connected with said capacitor for controlling the rate of charge thereof in accordance with signals, the arrangement being such that when said condenser is charged the potential on said one tube electrode trips said trigger circuit so that current flows in said other tube to discharge said capacitor.

9. A timing modulation system including in combination, a trigger circuit having a pair of electrode structures each provided with an anode, a grid and a cathode, impedance elements cross-coupling the anodes and grids of said structures in such manner that current normally flows in one electrode structure and is cut-off in the other electrode structure, a condenser shunted by a rectifier connected between the cathode of the normally cut-off electrode structure and ground, a pentode modulator tube having an anode and a grid, a connection from the anode of said modulator tube to the cathode of said normally cut-off electrode structure, and a connection from the grid of said modulator tube to a source of modulating signals.
